(57) **CLAIM**

The ornamental design for a stone rounding tool, as shown and described.

DESCRIPTION

FIG. 1 is a perspective view of a stone rounding tool showing my new design;

FIG. 2 is a top plan view thereof;

FIG. 3 is a front elevation view thereof, the rear being the same in appearance;

FIG. 4 is a bottom plan view thereof; and,

FIG. 5 is a left-side elevation view thereof, the right side being the same in appearance.

The designs shown in the stone rounding tool channels depict varying sizes of sanding grit.
